INVENTOR

William C. Rastetter

BY

A. G. Burns ATTORNEY

UNITED STATES PATENT OFFICE.

WILLIAM C. RASTETTER, OF FORT WAYNE, INDIANA.

METHOD OF MANUFACTURE OF LAWN-TENNIS-RACKET FRAMES.

Application filed June 15, 1923. Serial No. 645,570.

To all whom it may concern:

Be it known that I, WILLIAM C. RASTETTER, a citizen of the United States of America, and resident of Fort Wayne, in 5 the county of Allen and State of Indiana, have invented certain new and useful Improvements in Methods of Manufacture of Lawn-Tennis-Racket Frames, of which the following is a specification.

10 This invention relates to improvements in method of manufacture of lawn tennis racket frames, and the object thereof is to construct racket frames of bent wood in such manner as will obviate the tendency of 15 the racket frames to warp, and to eliminate the use of racket frame presses that are ordinarily used for retaining tennis rackets in proper condition. A further object of the invention is economy in the manufacture of 20 bent wood tennis racket frames.

These objects of the invention are accomplished by the construction illustrated in the accompanying drawings, in which:—

Fig. 1 is a front elevation of a tennis racket frame made in accordance with this invention;

Fig. 2 is a side elevation projected from Fig. 1;

Fig. 3 is a side elevation of a composite stock from which the frames are made;

Fig. 4 is a perspective view of the stock upon a reduced scale; and

Fig. 5 is a fragmentary view showing an elevation of a modified form of the invention.

The characters appearing in the description refer to parts shown in the drawings and designated thereon by corresponding characters.

40 In utilizing the invention a composite stock is first formed of a series of wide sheets of wood 1, 2, 3 and 4 glued together and bent so as to have a cross sectional shape of a tennis racket frame, there being a crotch piece 5 of wood glued into place between the ends of the innermost sheet 4 and also a cap-sheet 6 is glued to the top of the crotch piece and the surfaces of the sheet 4 adjacent thereto.

50 Ordinarily in the manufacture of tennis rackets the frame, when made of wood, is formed of one or more strips of wood which are subjected to a steaming process preliminary to being bent to the desired form, and it frequently occurs that after drying, the frames tend to warp more or less out of

shape. In the present instance, however, the sheets of wood are thoroughly dried and are given a preliminary sizing with thin glue and are subsequently laid together with 60 a binding coat of glue therebetween, and the wooden strata thus arranged are bent into the desired shape while the glue is viscous, the crotch piece 5 and cap sheet 6 being secured in place as the bending operation is completed. 65

The sheets of which the stock is formed are of much greater breadth than the thickness of a completed frame so that by sawing the stock in planes indicated by the dotted lines 7 numerous individual frames are made from a single stock. Prior to the sawing operations the stock is thoroughly dried so that the glue that unites the laminæ is set, and as the internal stresses in the various sheets, that are occasioned by bending the sheets from their normal planes, subside during the drying operation of the stock, the frames that are sawed from the stock retain a fixed shape and are not so susceptible to warping as the bent wood frames that are made singly in the usual manner. 75

80 In the modified form illustrated in Fig. 5, the ends of the innermost sheet 4' of the wooden strata are brought and secured together in the handle portion, and the crotch piece 5' terminates at the juncture of the ends of the sheet instead of continuing throughout the length of the handle portion 85 90 as in the former instance.

95 By preparing stock of sufficient width to admit of the sawing operations by which numerous frames are produced from a single stock, the usual number of bending operations in the quantitative production of frames is materially reduced, as in the present instance, a single bending and gluing operation suffices for the making of a multiplicity of frames with a corresponding economy, and more stable product as a result. 100

110 What I claim is:—

1. The method of manufacturing lawn tennis racket frames consisting in making a wide stock of bent wood laminæ in the form of a loop and with a crotch piece positioned between the end portions of the laminæ during the operation of bending the laminæ, and subsequently sawing the stock into numerous narrow portions forming a multiplicity of complete frames. 105 110

2. In the manufacture of lawn tennis racket frames, the formation of a wide stock composed of bent wooden laminæ glued together, the middle portion thereof being shaped into a loop, and a wooden crotch-piece positioned and glued between the end portions of the laminæ during the operation of bending the laminæ, the stock having a cross sectional shape of a racket frame, and subsequently sawing the stock into numerous narrow portions to form a corresponding multiplicity of complete frames.
3. A stock for making lawn tennis racket

frames comprised of bent wood laminæ and a crotch piece positioned between the end portions of the laminæ during the operation of bending the laminæ and having the cross sectional shape of a racket frame, and being of sufficient width to admit of making a multiplicity of complete racket frames by sawing the stock into a corresponding number of similar parts.

In testimony whereof I affix my signature.

WILLIAM C. RASTETTER.
